ENGINE SUPPLY SYSTEM

David Gregg, Caldwell, N. J., assignor, by mesne assignments, to Eclipse Aviation Corporation, East Orange, N. J., a corporation of New Jersey

Application September 24, 1931, Serial No. 564,951

14 Claims. (Cl. 123—119)

This invention relates to engine supply systems, and more particularly to an engine supply system wherein superchargers of different characteristics are used.

5 Superchargers for internal combustion engines are ordinarily of either the positive type or of the centrifugal type, both of which have inherent objectionable characteristics. The centrifugal type delivers large volumes and pressures at its 10 rated speed and is more compact and lighter than the positive type, but will not deliver sufficient pressure at starting or idling speeds. The positive type delivers its full pressure at low speeds, but mechanical limitations make it impractical for operation at very high speeds; hence 15 it is larger and heavier than the centrifugal type designed for some specific delivery conditions.

An object of the present invention is to provide an engine supply system wherein both types are 20 used and in which one supercharger, preferably the positive type, is automatically disengaged before high speed is attained.

Another object of the invention is to provide an engine supply system having a supercharger 25 arrangement wherein the low speed air supply is obtained from a positive type supercharger and the high speed air supply from a centrifugal type supercharger.

Another object of the invention is to provide 30 an engine supply system wherein a pair of superchargers of different discharge characteristics may efficiently supply a common discharge conduit.

Another object of the invention is to provide 35 an engine supply system wherein two superchargers may be employed without danger of diverting the air charge from the engine, irrespective of the driving connection of either supercharger.

40 Other objects of the invention will appear from the following description, in connection with which certain embodiments have been illustrated in the accompanying drawing, in which:

Fig. 1 is a somewhat diagrammatic view illustrating the improved arrangement of the inter-connected superchargers;

Fig. 2 is an enlarged view partly in section of the inter-connecting clutch;

Fig. 3 is an enlarged sectional view taken on the line 3—3 of Fig. 2; and,

Fig. 4 is a diagrammatic view illustrating a somewhat different embodiment of the invention.

In the drawing, with particular reference to Fig. 1, 10 is a carburetor adapted to have its dis-

charge opening 11 connected to an engine, not shown, and its inlet pipe 12 connected to the discharge opening of a positive type supercharger 13 which, in the illustrative embodiment, is of the sliding vane type and includes a housing 14 and an engine driven rotor 16 mounted eccentrically in the housing 14 and provided with a plurality of sliding vanes 17. Rotor shaft 18 is mounted in supports 19 by any desired means, such as bearings 21, and has its driving end connected with the engine driven shaft 22 by a centrifugal clutch, generally designated by 23 and which will be hereinafter more fully described. Inlet passage 24 of the positive type supercharger is connected to the outlet opening 26 of the centrifugal type supercharger, which includes a rotary impeller 27 secured to shaft 22, rotatably supported by bearings 28 and 29, and driven by means of pinion 31 and gear 32 having a shaft 33 operatively connected with the engine, not shown.

In the form illustrated, centrifugal clutch 23 which connects the positive and centrifugal type superchargers, comprises a driven spider 34 secured to shaft 18 by any desired means, such as set screw 36, and a driving disc 42 preferably slidably secured to shaft 22. A plurality of radially slidable centrifugal weights 37 are secured to spider 34 by stems 38, about which are springs 39 for urging them to their outer position. The inner ends of stems 38 are provided with stops 41 for limiting outward movement of weights 37 and preventing them from moving outwardly beyond a predetermined point. Disc 42 is preferably slidably mounted on shaft 22 by splines 43 and has a conical face 44 adapted to frictionally contact with the weights 37. An annular ring member 46 having a conical face 47 adapted to engage the opposite side of weights 37, is slidably mounted with respect to disc 42 by means of a plurality of pins 48 that are fixedly secured to disc 42 by threaded stems 49 and lock nuts 51. Annular friction member 46 is normally urged toward disc 42 by springs 53 that coat between the heads 54 of pins 48 and the outer surface of ring 46. Pins 48 are each provided with a groove 56 within which is a lock pin 57 axially slidable in opening 55 and normally held in the groove by a spring 59 coacting against flange 61 and the inner face of threaded plug 62.

In the low speed operation of the device, the impeller 27 of the centrifugal supercharger and the rotor 16 of the positive supercharger are both driven from the engine, for under low speed conditions, the centrifugal clutch 23 is in the posi-

tion illustrated in Fig. 3 and the opposed conical faces 44 and 47 are in frictional engagement with the wedge-shaped weights 37. If the speed of shaft 22 be increased beyond a predetermined point, the outward pressure of weights 37 is increased by centrifugal force and the inward pressure of springs 59 is reduced by the centrifugal force of pins 57, so that at the predetermined point, pins 57 move outwardly from the notches 56 and release the annular ring 46, whereupon it will be moved axially to its inoperative position by the outward force of weights 37. Disc 42 may also slide upon shaft 22 and be disengaged from the surface of weights 37, which have their outward movement limited by stops 41. If the speed of shaft 22 be decreased, the inward force of springs 59 is increased and pins 57 will have a tendency to move along the conical portions of pins 48 to again engage the grooves 56, which movement will be assisted by the action of springs 53. If desired, springs 53 may be eliminated and the inward movement produced by the selection of springs 59 of suitable strength.

In the engaged position of the clutch which preferably occurs during low speed operation, very little pressure is produced by the centrifugal supercharger and the engine is supplied principally by the positive type. After the predetermined speed has been reached, the centrifugal supercharger is able to produce the necessary pressure, and disengagement of the clutch permits the positive type supercharger to rotate idly and allow the air to pass therethrough on its way to the engine.

In the form of the invention shown in Fig. 4, the centrifugal and positive superchargers are arranged in parallel, whereby the inlet 71 of the positive supercharger and inlet 72 of the centrifugal supercharger each takes its supply of air from the atmosphere and delivers it through outlet conduits 73 and 74 respectively, to a common discharge outlet 76. In this form of the invention, outlet conduits 74 and 73 are each provided with check valves 77 and 78 respectively, which prevent either of the superchargers from discharging through the other when the delivery pressure of either is reduced below that of the other.

It may be readily seen from the above description that an engine supply system has been provided in which both a positive and a centrifugal type of supercharger are connected to a common outlet, and the positive supercharger is adapted to be automatically disconnected from the driving means at a point whereat the centrifugal supercharger develops sufficient pressure for delivery to the engine. It also may be seen that, as the positive supercharger is automatically disconnected, it may be made of small size, for there is no danger of seizure from excessive speed, and that it may be driven at sufficient speed to deliver a large quantity of air at comparatively low engine speeds.

While certain embodiments of the invention have been illustrated and described, it is understood that this showing and description are illustrative only and that the invention is not regarded as limited to the embodiments illustrated and described, or otherwise, except by the terms of the following claims.

What is claimed is:

1. In an engine supply system, a positive type supercharger, a centrifugal type supercharger, driving means therefor, and a centrifugal clutch

for disconnecting the positive type supercharger at a predetermined speed.

2. In an engine supply system, a pair of superchargers having different delivery characteristics, a common outlet for the superchargers, a centrifugally actuated device for disconnecting one supercharger at high speed, and spring means for reconnecting the same when the speed is reduced to a predetermined point. 5

3. In an engine supply system, a pair of superchargers having a common outlet and a common driving shaft, said shaft having aligned portions interconnected by a centrifugally actuated clutch for disconnecting one supercharger at a predetermined speed. 10

4. In an engine supply system, a positive and a centrifugal type supercharger having a common outlet and a common driving shaft, said shaft having aligned portions interconnected by a centrifugally actuated clutch for disconnecting the positive type supercharger at a predetermined speed. 20

5. In an engine supply system, a pair of superchargers having their discharge passages connected in series, driving means therefor, and means automatically operative at a predetermined speed of the supercharger for disconnecting the driving means of one supercharger from the main driving means. 25

6. In an engine supply system, a positive and a centrifugal type supercharger having their discharge passages connected in series, driving means therefor, and means operative at a predetermined speed for disconnecting the positive type supercharger from the driving means. 30

7. In an engine supply system, a positive and a centrifugal type supercharger, driving means therefor, said centrifugal type supercharger having its outlet connected to the inlet of the positive type supercharger, and means for disconnecting the positive type supercharger from the driving means at a predetermined speed. 40

8. In an engine supply system, a positive and a centrifugal type supercharger, driving means therefor, said centrifugal type supercharger having its outlet connected to the inlet of the positive type supercharger, and a centrifugally actuated clutch for disconnecting the positive type supercharger from the driving means at a predetermined speed. 45

9. In an engine supply system, a positive and a centrifugal type supercharger, driving means therefor, said superchargers having separate inlets and a common outlet, and a centrifugally actuated clutch for disconnecting the positive type supercharger at a predetermined speed. 55

10. In an engine supply system, a positive and a centrifugal type supercharger, driving means therefor, said superchargers having separate inlets and a common outlet, means for operatively disconnecting the positive type supercharger from the driving means at a predetermined speed, and means for preventing each supercharger from discharging through the other. 60

11. In an engine supply system, a pair of engine driven superchargers having a common outlet, means responsive to supercharger speed for operatively disconnecting one supercharger at a predetermined speed, said means including a latch device providing a quick release for the supercharger. 65

12. In an engine supply system, a pair of engine driven superchargers having a common outlet, means responsive to supercharger speed for operatively disconnecting one supercharger at a 70 75

predetermined speed, said means including a clutch having a member axially movable by centrifugal force to disengage the same, and a latch 5 radially movable by centrifugal force adapted to restrain axial movement of the member until the latch has been moved outwardly a predetermined amount.

13. In an engine supply system, a positive type supercharger, a centrifugal type supercharger, 10 driving means therefor, means for disconnecting the positive type supercharger at a predetermined speed, common discharge conduit for both super-

chargers and said centrifugal supercharger arranged to discharge through the positive supercharger.

14. In an engine supply system, a pair of superchargers having different discharge characteristics, a common outlet for both superchargers, a common driving shaft therefor said shaft being divided into two portions intermediate the superchargers, and a speed responsive clutch connecting the portions adapted to disconnect the 10 shaft portions at a predetermined speed.
